UNITED STATES PATENT OFFICE.

WILLIAM BOEKEL AND JULIUS BOEKEL, OF PHILADELPHIA, PENNSYLVANIA.

ATOMIZER.

SPECIFICATION forming part of Letters Patent No. 595,759, dated December 21, 1897.

Application filed July 29, 1897. Serial No. 646,307. (No model.)

To all whom it may concern:

Be it known that we, WILLIAM BOEKEL and JULIUS BOEKEL, citizens of the United States, residing at Philadelphia, in the county of 5 Philadelphia and State of Pennsylvania, have invented certain new and useful Improvements in Cut-Offs for Atomizers; and we do hereby declare the following to be a full, clear, and exact description of the invention, 10 such as will enable others skilled in the art to which it appertains to make and use the same.

This invention relates to the cut-off valves of atomizers or sprayers which discharge air into the outlet-passage of a receptacle for liquid, thereby forcing this liquid out with the air in a fine spray through a common discharge-nozzle. In practice after the flow of air has been cut off a certain amount of air-pressure continues briefly in the liquid-receptacle, often causing an inconvenient prolongation of the spraying after the nozzle of the atomizer has been withdrawn from the mouth or other part where the spray has been applied. To obviate this evil, a vent has 20 sometimes been made transversely through the plug and through the casing thereof at a point necessarily near the outlet-passage; but with such a construction there is during the normal operation of the atomizer a chance 25 of leakage at three points—namely, at the two ends of the bore in which the plug turns and through the additional hole for the vent. It becomes important to lessen the number of these apertures, and especially to do away with 30 the one which is most likely to cause a leak by reason of its proximity to the outlet which supplies the air-nozzle. To this end we make the vent-passage of the plug a longitudinal 35 groove extending from end to end thereof and discharging into the outer air at these ends, with no need for any additional aperture in the casing.

In the accompanying drawings, Figure 1 represents a side elevation of an atomizer embodying our invention. Fig. 2 represents a vertical section of the cut-off, its casing, and proximate parts; and Fig. 3 represents a detail perspective view of the same, the rotary plug being shown detached.

50 A designates the medicine-bottle or other receptacle for the liquid to be sprayed; B, the

outlet-nozzle therefor; C, the air-nozzle discharging into the tubular lateral extension B' of the upper end of said bottle; D, the liquid-discharge pipe, which extends from near the 55 bottom of the said bottle up to the tip of the spraying-nozzle B; E, the air-pipe supplying air under pressure through the air-nozzle aforesaid; F, the casing for the rotary plug G, which acts as a cut-off to the said air-supply and has its ends flush with the sides of the said casing; H, an operating-lever for the said plug or cut-off, mounted by arms h on studs g in the ends thereof and provided with a terminal thumb-piece H' and stop h', and I a 60 spring attached at one end to the top of the said casing and at the other to the under side of the said lever. This spring bends over the said casing when depressed and restores the said lever to its normal position when relieved from pressure. In the side of the said plug which is toward the air-discharge nozzle C we make a groove J, running from end to end thereof and communicating with the outer air at j. When the said plug is turned 70 to cut off the flow of air into the bottle, the said groove is in position to receive the air escaping from the said bottle and allow it to escape laterally from the atomizer without 75 driving any spray from the nozzle B. 80

The plug G fits into the usual transverse bore of the casing tightly enough to guard against leakage at its ends. These are the only possible points of such leakage, the only other openings of said casing being the inlet 85 and outlet for the passage of air to the nozzle. The air-vent groove or passage J is not necessarily extended to both ends of the said plug, as shown in Fig. 3, for an outlet at one end only will be operative; but the construction 90 of the said figure and as hereinbefore described in the specification is preferable as being more easily produced and affording more ample opening for escape.

Having thus described our invention, what 95 we claim as new, and desire to secure by Letters Patent, is—

1. In combination with the air-tube, air-nozzle and plug-casing of an atomizer, a rotary plug extending through the said casing 100 and provided with a longitudinal groove or passage that registers with the said nozzle and

extends through the end of the said plug making immediate connection with the outer air substantially as set forth.

2. In combination with the plug-casing of 5 an atomizer having an air inlet and outlet, a plug turning in said casing and extending through it at both ends, the said plug having a longitudinal groove formed therein, which extends through both ends of the said plug 10 and thereby makes a double connection with the outer air, while simultaneously communicating with the outlet substantially as set forth.

3. In combination with a liquid-receptacle 15 and a spraying-nozzle connected thereto, an air-nozzle discharging into the same, a cut-off plug for regulating the supply of air to said

air-nozzle, and a lever for operating the said plug, the latter being provided with a longitudinal groove which extends to the ends of 20 the said plug flush with the outer face of the casing and thereby directly connects the interior of the air-nozzle and bottle with the outer air when in position to cut off the supply of air from the said bottle substantially 25 as set forth.

In testimony whereof we affix our signatures in presence of two witnesses.

WM. BOEKEL.
JULIUS BOEKEL.
